UNITED STATES PATENT OFFICE.

ROBERT JOSEPH FISHER, OF ATHENS, TENNESSEE.

TYPE-WRITING MACHINE.

SPECIFICATION forming part of Letters Patent No. 690,715, dated January 7, 1902.

Application filed June 22, 1900. Serial No. 21,207. (No model.)

To all whom it may concern:

Be it known that I, ROBERT JOSEPH FISHER, a citizen of the United States, residing at Athens, in the county of McMinn and State of Tennessee, have invented a new and useful Type-Writing Machine, (Case B,) of which the following is a specification.

This invention relates to type-writing machines, and particularly to the construction and arrangement of the type-bars thereof to provide a low keyboard, visible writing, and a permanent alinement of the type with a minimum number of parts and low cost of construction. In the attainment of these results the invention primarily contemplates a modification of the construction and arrangement of type-bars disclosed in my companion application, (Case A,) Serial No. 21,206. While accomplishing all of the advantages of the construction set forth in the said other application, the present invention provides a novel manner of mounting and arranging the type-bars and their operating-shaft portions, whereby the type-bars are arranged at right angles to the axis of rotation of their operating-shafts and may be readily grouped in such a way as to provide a wide work-vista at the front of the type-basket to permit of a view of the writing from the front of the machine.

With these and other objects in view, which will hereinafter more fully appear, the invention consists in the novel construction, combination, and arrangement of parts hereinafter more fully described, illustrated, and claimed.

The improvements forming the subject-matter of the present application are necessarily susceptible to modification without departing from the scope of the invention; but the preferred embodiments of the improvements are shown in the accompanying drawings, in which—

Figure 1 is a plan view of a type-writing machine embodying the improved type-action. Fig. 2 is a front view of the machine. Fig. 3 is a vertical longitudinal sectional view thereof. Fig. 4 is a horizontal sectional view illustrating the grouping and arrangement of the type-bar-operating shafts and omitting the other parts of the machine for the purpose of clearly exposing the construc-

tion. Fig. 5 is a detail view showing a few of the individual bearings about the type-basket opening. Fig. 6 is a detail in perspective of one type-bar and its connections.

Like numerals of reference designate corresponding parts in the several figures of the drawings.

The present invention relates solely to the construction and arrangement of the type-bars in such a manner as to entirely dispense with the usual hanger-ring or support for the type-bar bearings, while at the same time providing a single direct operating connection between the type-bar proper and the keystem associated therewith. This improvement is necessarily susceptible to embodiment in almost any form of type-writing machine; but it is preferably utilized in the construction of a book type-writing machine of the type shown in my former patents, Nos. 569,491 and 573,868. The general form of the machine produced by embodying the novel construction and mounting of the type-bars is fully disclosed in the companion application, (Case A,) Serial No. 21,206, hereinbefore referred to, and a specific detailed description of the auxiliary appurtenances of this machine is not deemed necessary in the present case.

It is of course understood that in the carrying out of the invention the type-action, including the type-bars and the operating parts therefor, is necessarily carried by any suitable support; but for illustrative purposes the type-action, like in Case A, is shown in connection with a book type-writing machine having a traveling type-carriage 1, which is supported for travel in connection with suitable carriage or frame rails 2, coöperating with the main track-rails 3, which are associated with the type-writing-machine support or table 4, one of said carriage-rails 2 or the frame of which it forms a part carrying the usual line-spacing mechanism 5. As shown, the type-carriage 1 consists of a shallow or low casing provided with a flat base or floor 6, the inclosing side and front walls 7 and 8, respectively, and the top cover 9 of the usual stepped formation, over which is arranged the keyboard.

The improvements forming the subject-matter of the present application are designed to be associated with a suitable type-

basket opening within which the type-bars are grouped and which is open and freely exposed to permit of a clear view of the work, and in the horizontal form of carriage illustrated in the drawings the latter is provided in its rear side with a reentrant crescent or approximately semicircular type-basket opening 10. This arrangement of the type-basket opening within the rear side of the carriage permits the type-bars to strike rearwardly, thus permitting the carriage to be advanced forwardly or downwardly from the line of writing as the work progresses.

The present invention involves as an essential feature thereof the employment of a single type-bar 11, provided with an operating-rock-shaft portion 12, rigid therewith, so that for all practical purposes each type-bar and its operating rock-shaft will be of one piece. By reason of this construction each type-bar practically consists of the single bar or arm portion 11 and the operating-shaft portion 12, which move in unison and are operated by a direct key connection therewith. The type-bar and the operating-shaft may be constructed of one piece of material; but in the practical construction thereof the operation of welding will probably be resorted to to effect a rigid union between the type-bars and their shafts.

In adapting the type-bars and their operating rock-shafts to a horizontal type of machine, such as shown in the drawings, the said operating-shafts are all arranged in horizontal planes parallel with and in close proximity to the base or floor of the carriage-casing, thereby dropping the entire type-action into close relation to the writing plane. It is by reason of this arrangement that a very low keyboard may be provided in carrying out the present invention. The operating rock-shafts 12 for the type-bars extend forwardly from the type-basket opening 10 within the carriage-casing, and the type-bars themselves are grouped in a crescent form within the type-basket opening at the edge thereof. The said type-bars by reason of being disposed at direct right angles to the axis of rotation of their operating-shafts 12 will normally stand in vertical positions when at rest, and by grouping the type-bars in separate side banks or groups, which is rendered possible by the novel arrangement of the operating-shafts hereinafter more fully described, there is formed or provided at the center of the type-basket between the separate side banks of the type-bars a widened work-vista 13, which permits of a clear view from the front of the type-carriage into the type-basket opening 10 upon the writing or printing.

Each type-bar 11, or, more properly speaking, the operating rock-shaft 12 thereof, is provided with a pair of widely-spaced bearings 14 and 15, respectively, which bearings similarly consist of bearing brackets or plates arranged in upstanding positions and having formed therein bearing-openings 16 and 17,

respectively, which receive the opposite extremities of the operating rock-shaft associated therewith, and at this point it is to be observed that the bearing-openings in the widely-spaced bearings 14 and 15 for each rock-shaft are arranged in direct alinement and are intersected by a common plane, so as not to interfere with the free oscillation of the rock-shaft; but in order to permit of the right-angular disposition of each type-bar to the axis of rotation of its operating-shaft the operating-shafts for all of the type-bars excepting the type-bars at the very center of the type-basket are provided with laterally deflected or bowed portions 18, which sweep about the type-basket opening and permit of an exceedingly close grouping of the shafts, so that the straight portions of the latter may be brought toward the center of the carriage-casing into close or overlapping relation, as shown in Fig. 4 of the drawings.

The individual bearings 14 for the ends of the rock-shafts 12 contiguous to the type-bars 11 are grouped in circular series about the type-basket opening 10 and are seated, by means of a flange or other suitable connection 19, at the edge of the type-basket opening cut in the base or floor 6 of the type-carriage, as may be plainly seen from Fig. 3 of the drawings. The other individual bearings 15 are arranged remote from the type-basket opening in order to secure a maximum length of bearing for the individual type-bars, and inasmuch as most of the operating-shafts are longer than the type-bars proper the latter are positively prevented from any material play at the striking-point, which would interfere with the alinement of the type. The said individual bearings 14, located about the type-basket opening 10, are arranged side by side in as close relation as possible, with the bearing-openings 16 in their upstanding portions disposed in a direction to aline with the openings in the complementary individual bearings 15, remote from the type-basket opening; but in order to provide for the close grouping of the operating rock-shafts 12 within the bottom portion of the traveling type-carriage the said individual bearings 14 are necessarily of different lengths, so that the bearings for opposite sets of operating-shafts for the opposite banks of type-bars are necessarily arranged in different planes, which permits of the operating rock-shafts for the opposite banks of type-bars crossing each other in different horizontal planes, so that there is no interference between the shafts and their connections. This is plainly shown in Figs. 3, 4, and 5 of the drawings.

It will be further observed that the arrangement of the type-bar-operating shafts in the present case is quite similar to that disclosed in the other application, Case A, aforesaid; but it may also be noted herein that the series of operating rock-shafts 12 for one side bank of type-bars extend forwardly from the type-basket opening in divergent relation and are

disposed in one general direction, while the operating-shafts for the opposite side bank of type-bars bear a similar divergent relation to each other, but are disposed in an opposite direction toward the center of the type-carriage, whereby all of the operating-shafts will be bunched as closely toward the center of the carriage as possible. Most of the divergently-arranged operating rock-shafts for the opposite banks of type-bars will therefore necessarily cross each other, but in different horizontal planes, in view of the different planes in which the individual bearings are arranged.

15 The key connections are all alike, and the keys are arranged to form the keyboard in the usual way; but the present invention contemplates no interposed operating connections between the type-bar and the key therefore, as a direct motion is transmitted to each type-bar-operating shaft from the vertically-moving key-stem 20, working through the top cover 9 of the carriage-casing and having a pivotal connection at its lower end, as at 21, 20 with a short crank-arm 22, fitted to one end of the type-bar-operating shaft 12, associated therewith. This single and direct connection of parts is plainly shown in Figs. 3 and 6 of the drawings, and in connection with each 25 type-bar-operating shaft there is also employed a resetting or retracting spring 23, coiled upon the shaft and arranged to normally exert a torsional tension in a direction for returning the type-bars to their upright 30 positions after the type has been struck and the pressure of the finger relieved from the key.

35 The letter-spacing mechanism 24 and the yokes or universal connections 25 for such 40 mechanism are fully disclosed in the other application, (Case A,) so further reference thereto is unnecessary in the present application.

The construction set forth in this application constitutes one of the many modifications 45 which might be resorted to in the grouping of the type-bar-operating rock-shafts in close compact relation to permit of direct key connections therewith, so it will therefore be understood that various changes in the form, 50 proportion, and minor details of construction may be resorted to without departing from the principle or sacrificing any of the advantages of this invention.

Having thus described the invention, what 55 is claimed as new, and desired to be secured by Letters Patent, is—

1. In a type-writing machine, the combination with a series of type-bars arranged in crescent formation, of operating rock-shafts 60 rigid with said type-bars, a series of separate bearing members for the inner or rear ends of the rock-shafts, and operating-keys disposed in a plane above said shafts.

2. In a type-writing machine, the combination with a type-bar, of a laterally deflected or bowed operating rock-shaft rigidly con-

nected to said type-bar, and a key for operating said shaft and disposed in a plane above the same.

3. In a type-writing machine, the combination with a series of type-bars arranged in crescent formation, of laterally deflected or bowed operating rock-shafts rigidly connected to the type-bars, and operating-keys disposed in a plane above said shafts. 70

4. In a type-writing machine, the combination with a series of type-bars arranged in crescent formation, of laterally deflected or bowed operating rock-shafts rigidly connected to the type-bars, each of said type-bars being disposed at right angles to the axis of its rock-shaft, and operating-keys located in a plane or planes above said shafts. 80

5. In a type-writing machine, the combination with a series of type-bars arranged in crescent formation, of laterally deflected or bowed operating rock-shafts rigidly connected to said type-bars, each of said type-bars being disposed at right angles to its rock-shaft, a series of separate bearing members supporting the inner or rear ends of the rock-shafts, and keys for operating said shafts and located in a plane or planes above the same. 90

6. In a type-writing machine, the combination with a frame for the type-action having an approximately crescent-shaped type-basket opening, of a series of individual bearing members grouped about the edge of said opening, operating rock-shafts journaled in said bearing members, type-bars rigid with said operating-shafts and grouped in crescent form within the opening, and keys for operating said shafts and located in a plane or planes above the same. 95

7. In a type-writing machine, the combination with a supporting-frame for the type-action, said frame having a crescent-shaped type-basket opening, of a series of individual bearing members of different projection arranged about the edge of said opening, operating rock-shafts journaled in said bearing members, type-bars rigidly connected with the rock-shafts and arranged in crescent form within the type-basket opening, said rock-shafts extending away from the type-basket 110 and bearing an angular relation to each other, and keys for operating said rock-shafts. 115

8. In a type-writing machine, the combination with a supporting-frame for the type-action, said frame having a crescent-shaped type-basket opening, a series of individual bearing members arranged about the edge of said opening and of different projection, other bearings removed from the type-basket and paired with those about the opening, operating rock-shafts journaled in said paired bearings, certain of said shafts being crossed, and type-bars rigidly connected to said shafts and arranged in crescent formation about the edge of the type-basket opening. 120 125

9. In a type-writing machine, the combination with the keys, of a series of type-bars,

and operating rock-shafts rigidly connected to the type-bars and disposed at right angles thereto, said rock-shafts being extended under the keys.

5 10. In a type-writing machine, a support for the type-action having a crescent type-basket opening, a plurality of swinging type-bars provided with operating rock-shafts rigid therewith and extending forwardly of 10 said type-basket opening, all of said rock-shafts extending in divergent relation from the type-basket opening and bunched toward the center of the support for the type-action, and bearings for the operating-shafts ar- 15 ranged respectively about the type-basket opening and remote from the latter.

11. In a type-writing machine, a support for the type-action having an approximately crescent type-basket opening, a series of 20 closely-arranged individual bearings arranged about the edge of said opening and of different projection, other bearings arranged remote from the type-basket opening and paired with those about the opening, and 25 swinging type-bars provided with operating rock-shafts rigid therewith and journaled in the paired remotely-arranged bearings, all of said rock-shafts extending in divergent re-

lation away from the type-basket, and certain of which cross each other in different planes. 30

12. In a type-writing machine, the carriage provided within the rear side thereof with an approximately crescent type-basket opening, a series of individual bearings grouped about and arising from the edge of said opening, 35 said bearings being of different projection and disposed in staggered relation, other bearings fitted within the carriage-casing remote from those about the type-basket opening, and paired with the latter, and swinging 40 type-bars grouped within the type-basket opening and provided with operating rock-shafts journaled in the paired bearings, all of said rock-shafts extending in divergent relation forwardly of the type-basket opening and grouped or bunched toward the center of the carriage-casing, whereby certain of such shafts cross each other in different planes.

In testimony that I claim the foregoing as 50 my own I have hereto affixed my signature in the presence of two witnesses.

ROBERT JOSEPH FISHER.
